WELL CONDUCTOR PERFORATING GUN

Wilmerth E. Atwood, Odessa, Tex.

Application August 12, 1946, Serial No. 689,935

8 Claims. (Cl. 164—0.5)

1

This invention relates to new and useful improvements in well casing or pipe perforating guns.

It is one object of this invention to provide an improved well pipe or casing perforating gun which is simple and positive in action, and which insures proper perforation of the well casing or pipe in the desired manner.

An important object of the invention is to provide an improved well pipe or casing perforating gun in which the projectiles and powder charges along with the allied elements, may be readily removed and installed or adjustments made at the well site, where by return of the perforating gun to a servicing shop for minor adjustments or for reloading is not required.

Another important object of the invention is to provide an improved well pipe or casing perforating gun which may be unloaded from the rearward side of the gun chambers, so that a person working on the gun need not be in a position directly in the path of the projectile while unloading that particular gun unit.

Yet another object of the invention is to provide an improved well pipe or casing perforating gun wherein means are provided for disassembly of the gun elements without exposure and endangering of personnel, said means being effective to allow removal of the powder charge and/or the projectile; and wherein modifications may be provided to allow removal of the projectile chamber or sleeve and/or the barrel.

Still another object of the invention is to provide an improved well casing or pipe perforating gun wherein means are provided for conducting a propagated flame to and around the several gun elements and powder chambers, which means is effective to allow one powder charge to detonate others in the event of partial failure of the propagated flame so that mis-fires are substantially eliminated.

A further object of the invention is to provide an improved well casing or pipe perforating gun in which means are supplied for preventing the formation of burrs around the openings perforated in the casing or pipe by the projectile, said means being adapted to be carried with the projectile in its trajectory to remove effectively or prevent the formation of any burrs that would normally be formed by the projectile as it penetrates the well casing or pipe.

Still another object of the invention is to provide an improved well casing or pipe perforating gun wherein means are provided for effectively sealing off the projectile and powder cham-

2

bers against well fluid, thereby preventing damage to said chambers or their contents by the fluid, and insuring positive and efficient action by the perforating gun.

5 Yet another object of the invention is to provide an improved well casing or pipe perforating gun wherein an electrically fired cap detonates all of the powder charges substantially simultaneously, and which, with slight modification, may be adapted to fire each of these powder charges electrically.

A construction designed to carry out the invention will be hereinafter described together with other features of the invention.

10 15 The invention will be more readily understood from a reading of the following specification and by reference to the accompanying drawings, wherein an example of the invention is shown, and wherein:

20 Fig. 1 is a longitudinal, vertical, sectional view showing a well casing or pipe perforating gun constructed in accordance with the invention,

Fig. 2 is an enlarged, horizontal, cross-sectional view taken on the line 2—2 of Fig. 1,

25 Fig. 3 is an enlarged, fragmentary, vertical, sectional view taken on the line 3—3 of Fig. 1,

Fig. 4 is an enlarged, vertical, sectional view of the detonating unit,

Fig. 5 is an enlarged view, partly in elevation and partly in section, of the projectile and the associated sealing plate structure,

30 Fig. 6 is an enlarged, isometric view of the projectile,

Fig. 7 is a longitudinal, vertical, sectional view 35 of a modified form of the invention, adapted for use for electrical detonation and operation,

Fig. 8 is an enlarged, vertical, sectional view of one of the gun units,

Fig. 9 is an enlarged, horizontal, cross-sectional 40 view taken on the line 9—9 of Fig. 7,

Fig. 10 is an enlarged, vertical, sectional view taken on the line 10—10 of Fig. 8,

Fig. 11 is an enlarged, horizontal, cross-sectional view of a modified form of the gun element, and

45 Fig. 12 is an enlarged, horizontal, cross-sectional view of an additional modified form of the gun element.

In the drawings, the numeral 10 designates a 50 well casing or pipe perforating gun constructed in accordance with this invention. It is to be understood that the term "casing" as applied hereinafter to the gun is intended to cover casing, pipe, or any kind of a well fluid conductor. The 55 gun 10 is adapted to be lowered into a well bore

(not shown) which has a casing or other suitable conductor depending axially therein. A steel line or cable 11 suspends the gun within the well casing and said cable may be of any desirable and usual construction, preferably being of the type having an insulated electrical conductor 12 in its core. The gun 10 includes a head or supporting member 13 secured to the cable 11 by suitable means 14 which may be of any desirable form of rope socket, or joint, customarily used in making such connections.

A tapered, screw-threaded pin 15 is formed upon the lower end of the head 13, and an axial bore or passage 16 extends through the head. The bore 16 is reduced at its lower end to form a restricted passage 17, and a circular recess 18 is provided in the extreme lower end of the pin 15 in axial alignment with the bore 16 and passage 17. The electrical conductor 12 carried by the cable 11 extends downwardly from the retaining or securing means 14, through the bore 16 and the passage 17, the conductor having a snug fit within the latter passage. The conductor terminates within the recess 18 for purposes to be set out hereinafter.

A tool-joint or sub 19 depends from the head 13 by means of a screw-threaded box 20 formed upon the upper end of the sub, and which engages the screw-threaded pin 15. The sub 19 is substantially equal in diameter to the head 13, so that a substantially continuous external, cylindrical surface is provided by the joining of the two elements. The sub is formed with an axial bore or conduit 21 extending throughout the length of the sub, said bore being enlarged at its upper end and screw-threaded to receive a screw-threaded bushing 22. The bushing 22 is tubular and provided with an enlarged head 23 which engages within the recess 18 and rests upon the bottom of the box 20 and in snug engagement therewith. A longitudinal bore 24 extends axially of the bushing and receives an electrical detonating cap 25, (Fig. 4) which may be of any desirable type or construction. The cap 25 is provided with the usual flanged base 26 which is engaged between the bottom of the recess 18 and the enlarged head 23 of the bushing, whereby the cap is secured in place within the bore 24. The electrical conductor or cable 12 is provided with the usual conducting means (not shown) for establishing contact with the base of the shaft for detonating the latter by means of an electrical charge or current.

The lower end of the bore 24 is screw-threaded to receive a valve seat 27, positioned near the medial portion of the bore and adapted to be engaged by a valve ball 28. A ball-retaining collar 29 is positioned in the extreme lower end of the screw-threaded portion of the bore 24, and has its upper end conical in shape and formed at the apex with a concave ball rest 30. A bore or passage 31 extends upwardly within the ball-retaining member 29, terminating short of the upper end thereof, while lateral ports 32 directed upwardly and outwardly at an angle, communicate between the passage 31 and the bore 24 beneath the ball rest 30. Thus, under normal conditions, the valve ball 28 will be positioned, due to gravity, upon the ball rest 30, and unimpeded communication is provided from the cap 25 downwardly through the valve seat 27, the ports 32, and the passage 31 to the axial bore of the passage 21 of the sub 19.

As will be seen from the operation of the gun, when it is fired, a back pressure is exerted

upwardly through the bore 21. The effect of this pressure is to pick up the valve ball 28, and seat it against the valve seat 27, thereby preventing escape and loss of pressure within the gun body.

5 A reduced screw-threaded pin 33 is formed upon the lower end of the sub 19, and engages within a screw-threaded box 34 formed upon the upper end of a cylindrical gun body 35. The gun body 35 is substantially equal in diameter to the sub 19 and the head 13 to provide a continuous exterior surface, and is formed with a reduced screw-threaded pin 36 upon its lower end to carry additional gun bodies 36' similar to the body 35.

15 An axial bore or conduit 37, similar to the bore 21, extends longitudinally of the body 35, the bore 37 being enlarged and screw-threaded at its upper end to form a box 38 similar to that formed in the upper end of the sub 19, and adapted to receive the bushing 22. The box 38 is provided for use in instances where it is not desired to incorporate the sub 19 into the gun unit. In such an instance, the bushing 22 and cap 25 would be mounted within the box 38, and the pin 15 of the head 13 engaged within the box 34 carried by the gun body 35. Thus the utilization of the sub 19 is optional and dependent upon the operating conditions under which the gun is to be used.

30 The gun body is provided with a plurality of gun elements 39, and it is pointed out, that although only two elements are shown in the drawings, any desirable number may be utilized. In addition, any desirable number of gun bodies 36', similar to the body 35, and carrying any suitable number of gun elements, similar to the elements 39, may be incorporated into the unitary well conductor perforating gun. This feature lends great flexibility to the gun and to the usage 40 to which it may be put, since gun elements may be combined in any desirable number so as to be particularly adapted to the perforating operation at hand.

45 Each of the gun elements 39 includes a screw-threaded cylindrical box 40 formed in the outer wall of the gun body at one side thereof, and having its axis perpendicular to the longitudinal axis of the gun body. A similar, shallower box 41 is provided in the outer wall of the gun body diametrically opposite to the box 40 and in axial alignment therewith. The outer portion 42 of the box 41 is screw-threaded, while the inner portion 43 is reduced in diameter to form a powder chamber 44. A tapered bore 45 extends between the chamber 44 and the box 40, the bore 45 intersecting the longitudinal bore 37 of the gun body, and having its larger end directed toward the box 40. A tapered or conical sleeve 46 has a snug fit within the tapered bore 45, and terminates flush with the bottoms of the chamber 44 and the box 40. A cylindrical bore 47 extends axially of the sleeve 46 and is adapted to receive in snug sliding engagement, a bullet or projectile 48. An annular internal groove 49, rectangular in cross-section, is formed in the medial portion of the tapered bore 45 in vertical alignment with the bore 37 of the gun body, and a complementary annular groove 50 is formed upon the external surface of the tapered sleeve 46, the groove 50 being positioned medially of the sleeve so as to register with the groove 49. The bore 37 communicates with the grooves 49 and 50 above and below the sleeve 46, so that a continuous passage is provided through the bore 37 and around the 55 sleeve.

A plurality of radial ports 51 extend inwardly through the wall of the sleeve from the groove 50 to the bore 47, and a groove 52, similar to the groove 49, is formed in the wall of the bore 49 so as to encircle the bore and be in alinement with the ports 51. Communication is thus established between the groove 50 and the groove 52. An internal, longitudinal groove 50' extends from the groove 52 to the smaller end of the sleeve 46 along the wall of its bore 47.

The projectile 48 is reduced at its medial portion to form an annular groove 53 encircling the body of the projectile. The projectile is of the usual type, being cylindrical in configuration, and having a relatively pointed nose for facilitating penetration of the well casing or casings. A longitudinal groove 54 similar to the groove 50', is formed in the surface of the bullet or projectile and extends rearwardly from the groove 53 to the extreme rearward end of the projectile. In this manner, a continuous passageway is provided from the bore 37 through the grooves 49 and 50, the ports 51, the grooves 52 and 53, and the grooves 54 and 50' to a point adjacent the rearward end of the projectile, which is contiguous to the powder chamber 44.

The sleeve 46 is provided at its smaller end with an axial, circular recess 55 slightly larger in diameter than the bore 47, and a beveled internal flange 56 is formed upon the wall of the bore 47 at the bottom of the recess 55. The rearward face of the projectile 48 has its edge beveled so as to be complementary to the beveled flange 56 to permit the projectile to seat against said flange. Thus, the flange limits the rearward movement of the projectile within the bore and prevents the projectile from being forced into the powder chamber 44 and damaging the contents thereof.

A booster charge 57, in the form of a relatively thin disk is positioned within the recess 55 so as to abut the rearward face of the projectile and to be exposed to the open end of the groove 54 carried by the projectile. A powder charge 58 is disposed within the powder chamber 54, and may be of any desirable type or nature. There are a wide variety of propellant powders which may be used in conjunction with this type of gun, and it is contemplated to encompass the use of any of the powder types. The charge 58 is in the form of a relatively short cylinder so as to have a snug fit within the chamber 44 and a tight engagement with one face of the booster charge 57. A screw-threaded plug 59 engages within the screw-threaded outer portion of the box 41 to retain the powder charge in place and to absorb the recoil forces exerted by the powder charge when the gun is fired. The plug 59 carries on its outer end a polygonal recess 60 adapted to receive a suitable wrench of the Allen type (not shown) to permit unscrewing and removal of the plug. No portion of the plug 59 projects beyond the outer wall of the gun body 35, so that no obstructions are presented to the passage of the gun through the well bore.

A circular soft metal sealing disk 62 is positioned in the bottom of the box 40 so as to abut the larger end of the tapered sleeve 46. The disk 62 is formed with a double tapered opening 63 in its central portion, the opening being substantially equal in diameter to the diameter of the bullet or projectile 48, and being closed by a beveled soft metal disk 64 seated or secured within the opening. The disk may be held in place by a suitable sealing compound or by brazing

as is shown in Fig. 5 of the drawings, if desired. The disk 64 has its larger face directed outwardly toward the exterior of the gun body and is adapted to be carried with the projectile 48 in its trajectory to effect more efficient perforation of the well conductors, as will be more fully explained hereinafter. As is also shown in Fig. 5, the point or nose of the projectile may be secured to the disk 64 by embedding the nose therein and/or brazing the joint between the projectile and disk. In this manner, the projectile and plate may be inserted in the gun element as a unitary body and extraneous movement of the projectile within the bore 47 is prevented.

10 An externally screw-threaded barrel 66 engages within the box 40 to retain the plate 62 in place and to provide barrel means for the travel of the projectile 48. The barrel is provided with the usual bore 69 substantially equal in diameter to

20 the bore 47, and has formed on its outer end a polygonal pin 71 surrounding the bore 69 and adapted to receive a suitable wrench for removal of the barrel. Obviously, removal of the barrel 66 allows removal of the plate 62 and the projectile 48 along with the tapered sleeve 46. Also, removal of the plug 59 allows removal of the powder charge 58 from the outer chamber 44, along with the booster charge 57, or the booster charge may be removed through the box 40.

25 30 A second gun element is shown in Fig. 1 as being disposed below the uppermost elements 39, and in vertical alinement therewith. The second gun element is shown as adapted to fire a projectile in the opposite direction to the uppermost element. As pointed out hereinbefore, any suitable number of gun elements may be incorporated into the gun body 35, and any desirable number of gun bodies may be suspended one from another. It is also pointed out, that the gun elements may face in any desired direction so that any desirable portion of the casing or conductor may be perforated, it being customary in perforating guns, to stagger the arrangement of the guns so that substantially uniformly placed perforations are obtained in the well conductor.

35 40 In the operation of this form of the invention, the gun is lowered into the well bore upon the cable 11 to the desired point in the well bore where the perforation of the well conductor is to be carried out. After positioning, the electrical circuit is energized by suitable means (not shown), whereby an electric current is caused to flow in the electrical conductor 12, thereby detonating the electrically fired cap 25. The flame and burning gases created by the cap 25 travel downwardly through the bore 21, the box 38, and the bore 37 into the grooves 49 and 50. The flame is communicated from the grooves through the ports 51, the grooves 52 and 53, and the groove 54 to the booster charge 57, thereby detonating or exploding the latter. The explosion of the booster charge 57 sets off the main powder charge 58, which burns rapidly to propel the projectile 48 outwardly through the barrel 66. As the projectile commences its outward travel, the plate 64 is unseated or broken loose from the disk 62 and carried with the projectile through the barrel 69 and into contact with the well casing. As the projectile contacts and penetrates the well casing, 45 50 the soft metal plate 64 is deformed into the configuration of the nose portion of the projectile and flows rearwardly over said nose portion of the projectile to effect a wiping action around the edges of the perforation in the casing. This action effectively removes or prevents the formation

of upstanding burrs or other projections which might be formed by the projectile. Thus, the interior wall of the well conductor remains smooth and unobstructed after perforation.

This perforating gun is unusually safe to handle and to service by reason of the provision of the plug 59. If, for any reason, one of the gun elements does not fire, or the entire gun is removed from the well without firing, the gun elements may be unloaded from the rearward side by removing the plug 59 and the powder charge 44. The gun is then rendered safe and cannot fire accidentally. It is pointed out that this operation does not require exposure of the servicing personnel to the forward end of the gun element and injury of personnel by accidental discharge of the gun is minimized.

Should the travel of flame from the detonating cap be interrupted for any reason, the flame from an exploded powder charge would serve as a detonating flame, so that mis-fires are minimized.

A modification of the invention is shown in Figs. 7 through 10 of the drawings. This modification utilizes most of the structure described in connection with the first form of the invention, but is adapted for electrical firing of each gun element rather than the firing of a single electric cap with the resultant flame-propagated firing of the gun elements.

In the second form of the invention, the numeral 70 designates a head body similar to the head 13 and having a cable 71 secured to its upper end. The head 70 is provided with a depending screw-threaded pin 72 on its lower end and an axial bore 73. The bore 73 is enlarged at the lower end of the head to form a recess 74 which is enlarged further by counterboring to form an annular space 75 beneath the recess 74 and a shoulder 76. An electrical conductor 77, similar to the conductor 12, extends downwardly from the cable 71 through the bore 73, terminating in a contact face 78 positioned within the recess 74 surrounded by a cup-like insulator 79 to prevent shorting of the contact 78 of the head 70.

A sub 80 is provided with a screw-threaded box 81 on its upper end, which box engages the pin 72 to secure the sub 80 to the head 70. A longitudinal bore 81', relatively small in cross-section, extends throughout the length of the sub 80, and is enlarged at its upper end to form a screw-threaded box 82. A flanged insulating bushing 83 has engagement in the box 82 and is adapted to have its flange disposed within the counterbored portion 75 of the recess 74. The shoulder 76 engages the flange to form a snug joint. The bushing 83 is provided with an axial bore 84 substantially equal in diameter to the bore 81, and an electrical conductor 85 extends through said bushing and through the bore 81. A contact 86, similar to the contact 78, is recessed in the upper surface of the bushing 83 and is connected electrically to the upper end of the conductor 85. A recess 87, similar to the recess 74, is formed in the lower end of the sub 80, which is reduced and screw-threaded to form a screw-threaded pin 88, said recess being counterbored to form an enlarged portion 89 at the face of the recess 87. The lower end of the conductor 85 is electrically connected to a contact 90 positioned within the recess 87 and surrounded by a cup-like insulating member 91.

A gun body 92, similar in most respects to the gun body 35, is formed with a screw-threaded box 93' on its upper end so as to engage the pin 88

of the sub 80. A passage 93 extends longitudinally of the gun body 92, being substantially equal in diameter to the bores 73 and 81, and being enlarged at its upper end to form a screw-threaded box 94. A bushing 95 is disposed within the box 94 and carries a contact 96 in the same manner as the bushing 83 carries the contact 86. An electrical conductor 97 is disposed within the passage 93 and is connected electrically to the contact 96.

The lower end of the gun body 92 is reduced and screw-threaded to form a pin and a second gun body 92', similar to the gun body 92, depends from the pin.

A gun element 98 similar in nearly all respects to the gun element 39, is disposed transversely of the gun body 92 below the upper end thereof. As was pointed out in connection with the first form of this invention, any desirable number of the gun elements may be disposed within the gun body 92, although only two such bodies are shown, and any desirable number of gun bodies may be utilized. The only difference in structure is the inclusion of electrical conducting means within the gun element to conduct electric current to the electrical firing cap, which will be described hereinafter.

A circular electrical conductor 99 is disposed within the space enclosed within the grooves 49 and 50, the conductor being insulated from the gun body and from the tapered sleeve 46 with the exception of points exposed to the bore 93 on the outside of the conductor, and one point on the inside of the conductor overlying the port 51, only one of which is provided in this modification. The conductor 97 has its lower end exposed and in contact with the exposed portion of the conductor 99 upon the upper side of the sleeve 46, while a similar conductor 100 extending downwardly through the bore 93 below the uppermost gun element has its upper end exposed and in contact with the exposed portion of the conductor 99 on the lower side of the sleeve 46. Thus, electric current may pass through the conductor 97 to the circular conductor 99 and thence to the conductor 100 and so on down the body of the gun to each of the gun elements being utilized.

An electrical detonating cap 101 is disposed within the port 51 and has its base portion contacting the exposed part of the conductor 99 which overlies the port 51. Electric current is thus conducted to the cap by means of the circular conductor 99 so as to detonate the cap, when desired, and fire the gun. It is pointed out, that the circular conductor 99 is split at 102 diametrically opposite the cap 101 to allow the positioning of the conductor around the tapered sleeve 46.

In the operation of this modification of the invention, an electric current is passed down the conductor 73 within the cable 71 and is transmitted through the various contact points to the conductor 99, resulting in the firing of the cap 101. The flame and burning gases produced by the cap 101 pass through the port 51 to the grooves 52 and 53, and the groove 54 to the booster charge 57, detonating the charge 57 and thereby the main powder charge 58. The operation of the gun from this point onward is the same as that of the first form described.

This modified form of the invention provides the same safety features and efficient well conductor perforating means as the first form.

75 In Fig. 11 of the drawings is shown another

modification of the invention. This latter modification may be utilized with any of the preceding forms described and provides additional safeguards for operating personnel. The projectile-carrying sleeve as well as the powder charge may be removed from a specific gun element without necessitating exposure of the operator to the muzzle of the gun.

In this form, the numeral 110 designates a cylindrical gun body, similar to the gun bodies 35 and 92. The body 110 is provided with a transverse, diametric bore 111 having its central portion 112 tapered. The bore is adapted to receive a gun element 113 similar to the previously described elements. The larger end of the tapered central portion 112 of the bore 111 is directed toward the rearward side of the gun and gun element. The rearward end of the bore is enlarged to form a screw-threaded box 114, and the forward end of the bore is enlarged to form a similar screw-threaded box 115. A suitable screw-threaded plug 116 engages within the box 114 and a sealing disk 117, similar to the disk 62, is held within the box 115 by a screw-threaded barrel 118, similar to the barrel 66.

A tapered or conical sleeve 119 is disposed within the bore 112 and abuts the rearward or lower side of the disk 117. A projectile 120 is carried within the bore 121 of the sleeve, the barrel 118 having an alined bore 122. The gun body 110 and sleeve 119 are provided with matching circular grooves 123, similar to the grooves 49 and 50, while the sleeve carries radial ports 124 and internal grooves 125 and 125', similar to the ports 51 and the grooves 52 and 50' respectively, which were previously described. The projectile 120 is similar in all respects to the projectile 48, carrying the circular and longitudinal grooves described and having a booster charge 126 abutting its rearward face.

The rearward portion of the tapered bore 112 forms a powder chamber and receives a tapered or conical liner 127 which functions to hold the sleeve 119 in place and to contain a powder charge 128. The plug 116 engages the rearward edge of the liner to secure the liner and the sleeve in place within the tapered bore, and at the same time holds the powder charge in place.

Obviously, an operator of the gun may unscrew the plug 116, and thereby remove the powder charge and the tapered sleeve along with the projectile without exposing himself to the muzzle of the gun. The gun elements are normally arranged in staggered or spiral relation, but by beginning at one end of the gun and working toward the other, while keeping his body to one side of the adjacent gun elements, the operator may completely unload the gun without endangering his person.

In Fig. 12 a further modification is shown which allows removal of the gun barrel from the rearward side of the gun. This form is similar to the form shown in Fig. 11 except that the barrel 118 is not used. The box 115 is replaced with a tapered bore 130. The rearward, larger end of the bore 130 is less in diameter than the forward, smaller end of the bore 112 so as to form an annular shoulder 131 against which the sealing disk 117 seats. A tapered or conical barrel 132 is positioned within the bore 130 and held therein by the disk. The barrel is provided with a cylindrical bore 133 in alinement with the bore 121 of the sleeve 113. As shown, the remaining elements of this form are the same as the similar elements described in the previous

form and have been assigned the same numerals.

The provision of the tapered barrel prevents loss of the barrel in the well bore after firing of the gun. It is a relatively common occurrence for a screw-threaded barrel to become loosened after firing so as to project slightly from the gun body. In raising the body body to the surface, the gun barrels are rubbed against the well conductor, further loosening the barrels until they are entirely free. The barrels then often become wedged between the gun body and the inside wall of the well conductor resulting in a stuck perforating gun. Such an occurrence necessitates an expensive fishing job and holds up operations on the well.

With the present invention, the barrel cannot become loose and fall out of the gun body due to its tapered or conical construction. A definite advantage is thus achieved.

By removing the plug 116 in this modification, all the movable elements of the gun may be removed from the gun body, including the sealing disk and the barrel. The same safety features as pointed out hereinbefore obtain.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well casing perforating gun including, a gun body adapted to be lowered in a well bore, firing impulse conducting means extending axially of the body, means for suspending additional gun bodies from the uppermost body, each gun body having impulse conducting means extending axially thereof and intersecting a plurality of bores extending transversely of the bodies, a tapered sleeve disposed within each bore in vertical alinement with the conducting means, said sleeve having an annular groove about its circumference, the bodies having a mating groove formed in each of the bores, said grooves registering with the conducting means to make provision for conducting a firing impulse around the sleeve and to a lower sleeve, ports in the sleeves for conducting a firing impulse to the interior thereof, a projectile disposed within the sleeve, said projectile having an annular groove and a longitudinal groove for conducting a firing impulse to the rearward portion of the bore, a powder charge disposed within said rearward portion of the bore, a removable plug for holding said charge in place, and a removable barrel positioned in the forward end of the bore for holding the sleeve in place.

2. A well casing perforating gun as set out in claim 1, and a plate disposed between the sleeve and the barrel, said plate having a central opening therein and a beveled disk disposed in said opening, said disk being adapted to be separated from the plate by the projectile in its trajectory.

3. A well casing perforating gun including, a gun body adapted to be lowered into a well bore, a plurality of gun elements extending transversely of the gun body, an arcuate electrical conductor encircling each gun element, an electrical conductor extending above and between each of the gun elements and in contact with the arcuate conductors, a firing cap carried by each gun element and connected to the arcuate conductor, a powder charge in each gun element, and means

11

for conducting the firing impulse of the cap within the element to the firing charge.

4. A well casing perforating gun including, a gun body adapted to be lowered in a well bore and having a transverse bore, a gun element carried by the gun body and including, a projectile-carrying conical sleeve disposed within the bore, a barrel secured in one end of the bore, and a retaining element secured in the other end of the bore.

5. A well casing perforating gun including, a gun body adapted to be lowered in a well bore and having a transverse bore, a gun element carried by the gun body and including, a projectile-carrying conical sleeve disposed within the bore, a conical barrel secured in one end of the bore, and a retaining element secured in the other end of the bore.

6. A well casing perforating gun including, a gun body having a transverse bore, said bore being adapted to receive a gun element and being tapered so as to have its smaller end toward the muzzle of the gun element, a conical sleeve within the bore, a projectile within the sleeve, a conical powder chamber liner abutting the sleeve, a barrel secured in one end of the bore, and a retaining element secured in the other end of the bore.

7. A well casing perforating gun including, a gun body having a transverse bore, said bore being adapted to receive a gun element and being tapered so as to have its smaller end toward the muzzle of the gun element, a conical sleeve within the bore, a projectile within the sleeve, a conical powder chamber liner abutting the sleeve, a

conical barrel disposed in one end of the bore, and a retaining element secured in the other end of the bore.

8. A well casing perforating gun including, a gun body adapted to be lowered into a well casing, a flame conduit extending axially of the body, and a plurality of gun elements carried by the body, each element having a member for carrying a bullet bisecting said conduit, a powder-chamber adjacent said member and offset from said conduit, flame producing means connected with the conduit, and a check in the conduit between the flame producing means and the first gun element responsive to a back pressure in said conduit.

WILMERTH R. ATWOOD.
